UNITED STATES PATENT OFFICE.

GEORGE W. MILLER, OF SACRAMENTO, CALIFORNIA.

VENDING-MACHINE.

1,377,781.

Specification of Letters Patent. Patented May 10, 1921.

Application filed January 9, 1919. Serial No. 270,332.

To all whom it may concern:

Be it known that I, GEORGE W. MILLER, a citizen of the United States, residing at Sacramento, in the county of Sacramento 5 and State of California, have invented new and useful Improvements in Vending-Machines, of which the following is a specification.

This invention relates to a vending machine.

It is the principal object of this invention to provide a machine for vending small articles such as matches, chewing gum and the like, which machine will be decidedly simple in its construction and will operate in a manner to insure against choking of the supply hopper or the breaking down of any feed mechanism, thus making the device desirable from commercial and practical viewpoints. The present invention is particularly concerned with a feed hopper into which articles of rectangular shape may be disposed in a manner to be alternately withdrawn from the hopper by manual operation, as permitted by the release of a gate, which gate is preferably actuated by a coin control mechanism.

The invention is illustrated by way of example in the accompanying drawings, in which—

Figure 1 is a view in vertical section and elevation, illustrating the feed bin as disposed above the operating base and further disclosing the design of the control gates.

Fig. 2 is a view in section and elevation, as seen on the transverse center line of the machine.

Fig. 3 is a view in plan, as seen on the lines 3—3 of Fig. 1, illustrating the internal formation of the feed bin and the manner in which the articles to be vended are locked therein.

Fig. 4 is a view in section, as seen on the line 4—4 of Fig. 1, illustrating the sectional formation of the feed bin.

In the drawings, 10 indicates a base, here shown as rectangular in shape and formed by suitable vertical side walls connected at their upper edges by a platform 11. The 50 platform is horizontal and provides a support for a feed bin 12, within which the articles to be vended, are placed. In some instances, it may be found convenient to form the feed bin and the base as an integral 55 structure. As shown in the drawing, however, these members are separable. The bin

is provided with a pair of downwardly extending legs 13 which extend through slots 14 in platform 11. These legs are formed with outwardly projecting lugs 15 which 60 are engaged by flanges 16 carried by a change drawer 17. This drawer fits within the base, as clearly shown in Figs. 1 and 2 and is fitted with a locking lug 18 extending through an opening in the front side of 65 the base and which lug may be engaged by a padlock or lock pin. The said drawer with its flanges, thus coöperates with the lugs 15 to hold the bin and base together and these members are furthermore locked 70 against separation by the lock which engages the lug 18.

Reference being had to Fig. 4, it will be seen that the feed bin is substantially square in section, the corners being cut away as a 75 matter of design. The interior faces of the feed bin walls are formed with vertical grooves 19, 20, 21 and 22. The grooves 19 and 21 are exactly opposite each other and will receive the opposite ends of articles to 80 be vended, as indicated by the letter A. The grooves 20 and 22 are disposed opposite each other to receive the ends of articles B. These articles are alternately stacked criss-cross fashion within the bin and as the length of 85 the article is greater than the width of the article, they will be locked in position, as shown in Fig. 4.

At the bottom of the bin in the walls forming grooves 21 and 22, are cut away to form 90 outlet openings 23 and 24. These openings are of substantially the height of one of the articles to be vended and thus will permit the article to be drawn end-wise through the opening. It will be evident, however, that 95 a single article could only be drawn through the opening end-wise, as indicated by the article B in Fig. 3. In order to lock the bin so that this lowermost article cannot be normally withdrawn, an oscillating gate 100 member 25 is provided and pivotally mounted within the base. This gate member is formed with gates 26 and 27 which are represented by the fingers of the member 25. These gates are in fixed parallel relation to 105 each other and may be caused to alternately advance and recede through openings 28 and 29 formed in the platform 11 of the base. The openings 28 and 29 are so disposed in relation to the bin as to permit one 110 of the gate fingers to obstruct the bin opening 23 and the other gate finger to obstruct

the bin opening 24, the obstructing movement, however, being alternate. In the drawings, it will be recognized that the gate 27 is obstructing the movement of the article 5 B while the gate 26 has receded and would allow an article A to be withdrawn if it were so presented through the opening 23. The arrangement of the articles within the bin, however, prevents this withdrawal except in the manner to be further specified.

The gate member 25 is fixed upon a squared shaft 30 which is rotatably supported at its rear end by a hanger 31 and extends through a suitable opening at its 15 forward end where it is fitted with a knob or turning member 32. By rotation of the turning member, the gate-piece 25 may be actuated. It is desirable to prevent unlimited rotation of the gate-piece and it is 20 therefore provided with a locking quadrant 33. This quadrant is fixed to rotate in unison with the gate member and is formed with a pair of coin recesses 34 and 35. These recesses may alternately receive a coin 25 delivered through the slot 36 in the platform 11. The edge of the quadrant is formed in the usual manner with locking shoulders 37 and 38 which are alternately engaged by lock-springs 39 and 40. The 30 depth of the recesses 34 and 35 are such that when a coin is present in the recess presented to the slot 36, rotation of the quadrant will cause the coin to lift the locking spring from against its shoulder and permit 35 the gate member 25 to be moved so that one of the gates will move upwardly to an obstructing position and the other gate will move downwardly to permit the removal of one of the articles vended.

40 In the operation of the present invention, the bin 12 is filled with articles in the manner previously described and the lowermost article is obstructed by one of the gates. In the present instance, for example, the 45 article B is lowermost and could normally be withdrawn through the opening 24. This is prevented, however, by the upstanding gate 27. In order to obtain the article B, a coin is dropped through the slot 36 and 50 into the recess 35. The knob 32 is then rotated to move the quadrant in the direction of arrow a. The upwardly projecting edge of the coin will strike the free end of the lock-spring 40 and raise it from its obstructing position in relation to the shoulder 38. This will cause the gate member 25 55 to swing and will cause a simultaneous downward movement of the gate 27 and an upward movement of the gate 26, the length 60 of these gates being so designed as to insure that when the gate 27 starts downwardly from its locking position, the gate 26 will start upwardly to an obstructing position or vice versa. The knob is turned until the 65 lock spring 39 falls in rear of the shoulder

37, at which time the gate member will be locked against backward movement. This will have caused the gate 27 to move out of the way of the article B and will permit it to be withdrawn by removal in the direction 70 of arrow b, as indicated in Fig. 3.

It will be understood that when this article is withdrawn, the entire stack will fall and the lowermost article A will then stand in position to be withdrawn through the 75 opening 23 while obstructing the opening 24. By repeating the operation, as previously described, the article A may be withdrawn and by alternately operating the gate member, the contents of the entire bin may be 80 withdrawn, one article at a time.

It will thus be seen that the vending machine here disclosed, while simple in its construction and composed of few parts, will operate efficiently to prevent indiscriminate 85 removal of the articles vended and to insure that they will be held until the proper mechanism has been actuated. It will be further evident that the parts of the device may be readily made of glass, if desired, 90 thus rendering the device cheap in construction and attractive in appearance.

While I have shown the preferred form 95 of my invention, it will be understood that various changes in the combination, construction and arrangement of parts may be made by those skilled in the art, without departing from the spirit of the invention as claimed.

Having thus described my invention, what 100 I claim and desire to secure by Letters Patent is—

1. A vending machine comprising a bin in which articles to be vended may be stacked, and having outlet openings at the 105 bottom thereof, means for admitting the lowermost of said articles to be withdrawn from the bottom of said stack, and a rocking gate member adapted to alternately obstruct said openings to permit one article to be withdrawn at a time, a quadrant turnable in unison with the gate member, and having coin pockets, and springs releasable by the insertion of a coin.

2. In a vending machine, a feed bin 110 adapted to receive articles of rectangular shape, a pair of openings at the bottom of said bin for permitting the articles to be withdrawn therefrom, the inner walls of the bin being longitudinally grooved to receive 115 and permit the articles to be alternately withdrawn from said openings, a pair of gate members simultaneously movable for alternately obstructing the openings in the bin, and coin control means to lock or release the gate members.

3. In a vending machine, a vertical bin within which a plurality of articles may be stacked in criss-cross fashion, said bin having a pair of openings through its side walls, 120

through which the lowermost of the articles may be withdrawn endwise, and lock means for normally obstructing the opening, from which it is possible to withdraw an article.

- 5 4. In a vending machine, a vertical bin within which a plurality of articles may be stacked in criss-cross fashion, said bin having a pair of openings through its side walls, through which the lowermost of the articles 10 may be withdrawn endwise, lock means for alternately obstructing the opening, from which it is possible to withdraw an article, and a coin control means controlling said locking means.
- 15 5. A vending machine comprising a vertical bin having dispensing openings at the bottom of two of its adjacent side walls and through which articles to be dispensed may be alternately withdrawn, and an oscillating 20 gate member formed with a pair of obstructing fingers adapted to be alternately disposed in an obstructing position before the openings whereby the articles may be alternately withdrawn from the openings.
- 25 6. A vending machine comprising a vertical bin having dispensing openings at the bottom of two of its adjacent side walls and through which articles to be dispensed may be alternately withdrawn, an oscillating 30 gate member formed with a pair of obstructing fingers adapted to be alternately disposed in an obstructing position before the openings whereby the articles may be alternately withdrawn from the openings and 35 coin control means for said oscillating member.

7. A vending machine comprising a vertical bin having longitudinal grooves in each of its sides, the grooves of opposite walls 40 receiving the ends of rectangular articles to be dispensed, which articles are arranged

criss-cross and alternately superimposed within the bin, an opening at the bottom of two adjacent walls through which the dispensed articles may be withdrawn, a base 45 member upon which the bin is mounted and an oscillating lock member formed with two fingers adapted to alternately move to an obstructing position in front of the openings of the bin, thereby permitting the articles 50 within the bin to be alternately withdrawn from the two openings in the bin as the oscillating member is moved from one position to another.

8. A vending machine comprising a vertical bin having longitudinal grooves in each of its sides, the grooves of opposite walls receiving the ends of rectangular articles to be dispensed, which articles are arranged criss-cross and alternately superimposed within the bin, an opening at the bottom of two adjacent walls through which the dispensed articles may be withdrawn, a base member upon which the bin is mounted, an oscillating lock member formed with 60 two fingers adapted to alternately move to an obstructing position in front of the openings of the bin, thereby permitting the articles within the bin to be alternately withdrawn from the two openings in the bin as 65 the oscillating member is moved from one position to another, and coin control means associated with said oscillating member to permit movement thereof.

In testimony whereof I have hereunto set 75 my hand in the presence of two subscribing witnesses.
